CLOSURE FOR CONTAINERS

Herbert O. Hoffman, Ashland, Ohio, assignor to
The Faultless Rubber Company, Ashland, Ohio,
a corporation of Ohio

Application November 12, 1938, Serial No. 240,185

2 Claims. (Cl. 215—43)

This invention relates to closures for containers, and has for an object the provision of new and improved devices of this character.

In the drawing accompanying the specification, and forming a part of this application, I have shown, for purposes of illustration, one form which my invention may assume, and in this drawing:

Figure 1 is an elevational view, showing an illustrative embodiment of my invention as applied to a bottle,

Figure 2 is a fragmentary vertical sectional view, drawn to an enlarged scale and corresponding substantially to the line 2—2 of Figure 1, and

Figure 3 is an enlarged vertical sectional view of the closure, removed from the bottle.

The embodiment of the closure herein shown comprises cap means 10, having a skirt portion 11 and a top portion 12. The cap means 10 is preferably formed of substantially rigid material, such as hard rubber or other plastic composition. The exterior of the skirt portion 11 is roughened, such as by fluting 13 herein shown, or as by knurling or the like, to provide a surface which may be readily grasped by a user of the closure. The interior of the skirt portion 11 is formed with interior screw-threads 14, adapted to cooperate with exterior screw-threads 15 formed on the neck 16, of a container, such as the bottle 17 herein shown.

Extending inwardly of the cap means 10, from the inner surface 18 of the top portion 12, is a tapering projection 19 providing an annular inclined sealing surface 21. At least a part of the projection 19 is adapted to extend within the opening 22 of the bottle neck 16, and the surface 21 is constructed and arranged to engage the lip surrounding the bottle opening 22 in sealing relation, as best shown in Figure 2.

It is recognized that there are on the market closures for the purpose of the present closure, but provided with an interior washer that is more or less compressible, to serve as a sealing means; however, with the present closure the use of any such washer is entirely unnecessary.

From the foregoing it will be apparent to those skilled in the art that I have accomplished at

least the principal object of my invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

10

I claim:

1. A closure for a container having a neck surrounding the opening into the container, comprising: cap means, formed of hard plastic material, having a skirt portion adapted to embrace the neck of the container, and having also an integral top wall adapted to overlie the opening into the container, said top wall having an integral substantially frusto-conical projection formed of hard plastic material, extending from the inner surface of said top wall and adapted to seal the opening into the container, the inclining wall of said projection being so constructed and arranged as to have limited peripheral surface contact with the surface defining the lip of the opening, the terminating surface of said projection being substantially flat and so arranged with respect to said inclining wall as to extend not materially beyond the terminating margin of the neck.

30

2. For use with a bottle having a neck formed with a substantially cylindrical opening terminating in an annular small radius fillet merging with the terminating margin of the neck, a closure comprising: cap means, formed of hard plastic material, having a skirt portion adapted to embrace the neck, and having a top wall adapted to overlie the terminating margin of the neck; and sealing means, for sealing said bottle opening, formed of hard plastic material, carried by said cap means to extend from the inner surface of said top wall, and having a substantially conical defining wall so constructed and arranged as to have substantially line peripheral surface contact with the surface defining the annular fillet.

HERBERT O. HOFFMAN.
